UNITED STATES PATENT OFFICE.

ALEXIS F. GILLET, OF OMAHA, NEBRASKA.

DESIGN FOR A TACK-PULLER.

42,279.

Specification for Design.

Patented Mar. 12, 1912.

Application filed August 19, 1911. Serial No. 645,036. Term of patent 14 years.

To all whom it may concern:

Be it known that I, ALEXIS F. GILLET, a citizen of the United States, residing at Omaha, in the county of Douglas and State of Nebraska, have invented a new, original, and ornamental Design for a Tack-Puller, of which the following is a specification, reference being had to the accompanying drawing, forming a part thereof.

Figure 1 is a side view of a tack puller, showing my new design. Fig. 2 is a plan view of the bottom or lower side of the tack puller, and Fig. 3 is an end view of the same.

The chief feature of the design is the shape of the integral casing and fulcrum-wheel.

I claim:

The ornamental design for a tack puller as shown and described.

In testimony whereof I have affixed my signature in presence of two witnesses.

ALEXIS F. GILLET.

Witnesses:

HEIRAM A. STURGES,
